Attorney

UNITED STATES PATENT OFFICE.

CHARLES CRETORS, OF CHICAGO, ILLINOIS.

CORN-POPPING APPARATUS.

SPECIFICATION forming part of Letters Patent No. 728,550, dated May 19, 1903.

Application filed August 28, 1902, Serial No. 121,815. (No model.)

To all whom it may concern:

Be it known that I, CHARLES CRETORS, a citizen of the United States of America, and a resident of Chicago, in the county of Cook and State of Illinois, have invented certain new and useful Improvements in Corn-Popping Apparatus, of which the following is a specification.

The present invention relates to that type of corn-popping apparatus in which as the popping operation progresses the popcorn is discharged from the popping-pan as fast as the same pops open; and the object of the present improvement is to provide a simple and efficient construction and arrangement of parts which is adapted to afford a ready and convenient control of the driving connections of the stirrer mechanism by the operator and an automatic discharge of the completely-popped corn as fast as formed during the progress of the popping operation and by means of which the usual clogging of the stirrer-blades is prevented in a very effective manner, all as will hereinafter more fully appear, and be more particularly pointed out in the claims.

In the accompanying drawings, illustrative of the present invention, Figure 1 is a side elevation, with the roasting-pan in section, of a corn-popping apparatus embodying the present improvement; Fig. 2, an enlarged detail vertical sectional elevation of the middle portion of the apparatus, taken at line *x* *x*, Fig. 1; Fig. 3, a fragmentary bottom plan of the cover portion of the apparatus; Fig. 4, a detail plan view of the stirrer-blades and their carrying-hub; Fig. 5, a side elevation of the lower portion of the vertically-arranged driving-shaft of the stirrer; Fig. 6, an enlarged transverse section of one of the stirrer-blades, taken at line *x'* *x'*, Fig. 4.

Similar numerals of reference indicate like parts in the several views.

Referring to the drawings, 1 represents the usual shallow roasting-pan, open at top and provided with a flat bottom. Such pan is removably supported in any usual manner above a gas-burner or other heater employed to heat the bottom of the pan.

2 is a handle at one side of the pan to afford convenient means for handling said pan.

3 is a central fixed bearing-bushing fixedly secured to the bottom of the pan 1 by means of a reduced and screw-threaded extension at its lower end, which passes through a central orifice in the pan-bottom to be engaged by a clamping-nut 4. The upper end of the bearing-bushing 3 is preferably of a cone shape to form a bearing for the stirrer-hub hereinafter described, and in addition such bearing-bushing is formed with an axial counterbore that ends in an annular abutment-shoulder 5 at its upper end, all as illustrated in Fig. 2 of the drawings.

6 is the carrying-hub of the stirrer-blades, 65 formed to fit over and have bearing upon the stationary bearing-bushing 3 of the pan 1. To this end said hub will have its central bore formed with an upper screw-threaded portion, an intermediate coned bearing-surface 7, 70 adapted to fit and have bearing upon the coned upper end 8 of the bushing 3, and a lower circular bearing-surface 9, adapted to fit and have bearing against the lower periphery of said bushing 3, as illustrated in Fig. 2. 75

10 is an inner sleeve or extension of the stirrer-hub 6, formed with a reduced screw-threaded upper end adapted to screw into the aforesaid screw-threaded upper portion of the bore of the hub 6 and be locked in position by a radial set-screw arranged in said hub. Such sleeve or extension is also formed with an enlarged lower body portion adapted to have upward bearing against the abutment-shoulder 5 of the bearing-bushing 3 to prevent any tendency on the part of the stirrer-blades and hub to an independent upward movement with relation to the pan-bottom and the bearing-bushing. Such sleeve or extension is also formed with a non-circular bore 85 extending the vertical length of the same and adapted for engagement from either end by the non-circular end of a driving-shaft, from which motion is imparted to the rotary stirrer of the present construction. 95

12 is a vertical shaft having a non-circular lower end, which is preferably of the tapering and squared form shown in Fig. 2 and adapted to have operative engagement in the upper end of the non-circular bore of the 100 sleeve 10 in a readily-detachable manner and so that such shaft and the pan-cover herein-

after described may be lifted vertically to permit the removal of the pan and stirrer for cleaning and like purposes.

13 is a non-circular orifice in the lower end 5 of the sleeve 10, adapted to receive the non-circular shank of a suitable wrench by which the sleeve 10 is held from rotation while the stirrer-hub 6 is being unscrewed therefrom in the operation of taking the mechanism 10 apart.

14 represents a series of radially-arranged stirrer-blades, secured in recesses in the under side of the stirrer-hub 6, by rivets or other equivalent means, in a manner to insure a 15 contact of the full length of such blades with the flat bottom of the pan 1. In the present improvement such blades will have an oblique arrangement with relation to the pan-bottom, with their upper surfaces ground down to a 20 knife-edge in manner illustrated in Fig. 6 and preferably by a concave grinding away of the blades, as shown. By such arrangement and construction the adherence of the butter used in the corn-popping operation, 25 with the gradual accumulation of chaff, fuzz, &c., upon the forward edges of the stirrer-blades, is prevented in a very efficient and perfect manner.

15 is the pan-cover, of any usual form, preferably of the cone shape shown, and adapted 30 to normally close the open top of the pan 1 in a loose manner. 16 is a central tubular hub on said cover, the central vertical bore of which is formed with an internal screw- 35 thread, as shown, which has operative engagement with a lateral tooth or pin 17 on the side of the driving-shaft 12, so that the cover is wholly supported thereby in the vertically-adjustable and automatic manner now 40 to be described.

With the commencement of the operation the bottom portion of the pan 1 is filled with raw popcorn and the cover 15 lowered to close the open top of the pan. As the corn 45 gradually pops the same increases in volume and presses upward against the under surface of the cover 15 to cause the same to rise vertically, and such rising movement of the cover will continue with the progress of the 50 popping process until the cover is a distance wholly above the top of the pan 1, after which the fully-popped and comparatively light corn will flow over the edge or margin of the pan 1 and fall into a suitable receiver. In the 55 present construction the described vertical rising of the cover 15 is aided in a positive manner by the lateral stud 17 of the shaft 12 moving downward in the internal screw-thread of the cover carrying hub 16, while 60 the cover is held from rotation by contact of the popped corn against the under surface of the cover, as above set forth.

18 is a radial web secured to the under surface of the cover 15 and adapted to aid in the 65 retarding action upon the cover above set forth.

19 is a circular flange on the tubular hub

16, to which the central portion of the cover 15 is secured by rivets or other equivalent means.

20 is an inverted-cone-shaped bracing-web secured to the under surface of the cover 15, with its lower inverted point portion bearing upon the lower portion of the tubular hub 16 to afford stiffness to the cover and strength to 75 the attachment of the cover to said hub.

Having thus fully described my said invention, what I claim as new, and desire to secure by Letters Patent, is—

1. In a corn-popping apparatus of the character described, the combination of a stationary shallow pan having an open top and a flat bottom, a journal-bushing secured centrally to said bottom, and a rotary stirrer comprising a central hub having bearing upon said bushing and a series of radial blades arranged obliquely to the surface of said bottom and having their upper surfaces ground down to a knife-edge, substantially as set forth.

2. In a corn-popping apparatus of the character described, the combination of a stationary shallow pan having an open top and a flat bottom, a journal-bushing secured centrally to said bottom, and a rotary stirrer comprising a central hub having bearing upon said bushing and provided with a non-circular bore and a series of radial blades carried by said hub, a driving-shaft having a non-circular end adapted for operative engagement with the stirrer-hub a lateral tooth or pin on said shaft, a pan-cover and a central hub carrying said cover and provided with an internally-screw-threaded bore adapted for operative engagement with the lateral tooth of the driving-shaft, substantially as set forth.

3. In a corn-popping apparatus of the character described, the combination of a stationary shallow pan having an open top and a flat bottom, a journal-bushing secured centrally to said bottom, and a rotary stirrer comprising a central hub having bearing upon said bushing and provided with a non-circular bore and a series of radial blades carried by said hub, a driving-shaft having a non-circular end adapted for operative engagement with the stirrer-hub, a lateral tooth or pin on said shaft, a pan-cover, a central hub carrying said cover and provided with an internally-screw-threaded bore adapted for operative engagement with the lateral tooth of the driving-shaft, and a radial web secured to the under side of the pan-cover, substantially as set forth.

4. In a corn-popping apparatus of the character described, the combination of a stationary shallow pan having an open top and a flat bottom, a journal-bushing secured centrally to said bottom, a central stirrer-hub having a central bore formed with an upper screw-threaded portion and an intermediate lower bearing-surface, an attaching-sleeve having an enlarged lower end engaging the pan-bushing aforesaid and a screw-threaded upper end engaging the screw-threaded bore of the stir-

rer-hub, and a series of radial blades secured to said hub, substantially as set forth.

5. In a corn-popping apparatus of the character described, the combination of a stationary shallow pan having an open top and a flat bottom, a journal-bushing secured centrally to said bottom, and a rotary stirrer comprising a central hub having bearing upon said bushing and provided with a non-circular bore and a series of radial blades carried by said hub, a driving-shaft having a non-circular end adapted for operative engagement with the stirrer-hub, a lateral tooth or pin on said shaft, a pan-cover, a central hub carry-

ing said cover and provided with an internally-screw-threaded bore adapted for operative engagement with the lateral tooth of the driving-shaft, and an inverted-cone-shaped bracing-web connecting the cover and the lower portion of its carrying-hub together, substantially as set forth.

Signed at Chicago, Illinois, this 26th day of August, 1902.

CHARLES CRETORS.
